DEGREASING PROCESS

Wolcott Dennis, Basking Ridge, and John Joseph Rendos, Millington, N.J., assignors to Air Reduction Company, Incorporated, New York, N.Y., a corporation of New York

Application May 31, 1956, Serial No. 588,340

4 Claims. (Cl. 134—22)

This invention relates to a vapor-phase degreasing process, and particularly to a method of degreasing, at relatively low temperatures, liquefied gas installations employed in the handling, storage and distribution of low temperature liquefied gases. The term "liquefied gas installations" will be used hereafter to mean all apparatus such as storage tanks, trailers, vaporizers, fractionation columns, etc. used in the manufacture, handling, distribution and storage of low temperature liquefied gases such as liquid oxygen, liquid nitrogen, liquid argon and the like.

When liquefied gas installations such as liquid oxygen tanks have been in service for a considerable time, there is an accumulation of oil, grease and similar material on the walls of the apparatus. This accumulation is objectionable and troublesome if not removed. Heretofore, these accumulations have been eliminated by washing with water soluble cleaners such as sodium metasilicate. Briefly, this method of degreasing requires warming the system to a temperature above the freezing point of water (+32° F.), circulating a large quantity of hot cleaning solution through the system, thorough flushing of the system to remove all traces of washing solution, thorough drying by continued circulation of a hot inert gas to remove all moisture from the system, and cooling the system before restoring it to service.

If the system is not thoroughly washed and dried, the small lines may become clogged with undissolved salts from the wash solution or with particles of ice formed by the freezing of free unremoved water. Furthermore, it is virtually impossible to analyze the large amount of wash liquid employed in this method of degreasing for the relatively small quantity of oil and grease removed. In addition, the apparatus is susceptible to severe corrosion from the degreasing solvent, if said solvent is used in excessive concentrations. This is especially true when installations of aluminum or copper are being cleaned.

To service an installation having a 100,000 standard cubic foot capacity would require approximately 75 man hours using the present method of degreasing. A wash trailer having a 1500 gallon capacity is also required to service such an installation and a supply of steam, water and electricity are needed to effect the desired cleaning. With the instant invention the same installation can be serviced in 10½ hours and the only utility required is electricity.

It is, therefore, an object of this invention to reduce the time required to clean low-temperature liquefied gas installations and to avoid some of the difficulties involved in the use of water soluble cleaners.

Another object of this invention is to provide a method of degreasing liquefied gas installations wherein the cleaning operation may be initiated at low temperatures.

Another object of this invention is to provide a method by which low temperature liquefied gas installations can be efficiently and effectively cleaned with maximum simplicity and a minimum of materials and services.

These and other objects and advantages of the invention will be pointed out or will become apparent from

2

the following detailed description and the accompanying drawing.

According to the present invention these objects are achieved by removing the liquid content from the liquefied gas installation, establishing the temperature of said installation above the melting point but below the boiling point of the degreasing solvent to be used, vaporizing said solvent, admitting the solvent vapors to the installation, condensing said vapors on the walls of the installation; 10 withdrawing the condensed vapors containing the oil, grease and similar contaminants removed from the walls of said installation, and purging the installation with a suitable dry gas such as nitrogen or air.

An important aspect of the invention resides in the 15 selection of a suitable solvent. One such solvent that has been found to give excellent results is trichloromonofluoromethane (i.e. CCl_2F) which has a melting point of —168° F. and a boiling point of +75° F. Trichloromonofluoromethane is sold under the trade name Feron 20 11 and will be referred to hereinafter as such. Since Freon 11 has a melting point of —168° F., the applicant found that the cleaning cycle could be initiated at about —160° F. or slightly above the melting point of the Freon 11. It was also discovered that removal of the 25 residual Freon 11 from the installation could be affected by simply purging the system with a suitable gas, preferably heated to a temperature slightly above the boiling point of the Freon 11. Moreover, Freon 11 is particularly applicable for practicing the method of the instant invention since it not only has low melting and boiling points, but is also substantially noncombustible, nontoxic and inert.

It has likewise been discovered that several saturated and unsaturated halogenated derivatives of methane and 35 ethane having melting points about between —124° F. and —256° F. and boiling points about between +187° F. and —41° F. may be used as solvents to practice the method of the instant invention. These halogenated derivatives of methane and ethane correspond to the general formula: $C_wH_xCl_yF_z$ where w is one or two; x is zero or one; and y and z are integers of from zero to four. It is understood that the term integer as used herein shall be construed to include zero.

The single figure of drawing illustrates diagrammatically 45 one form of suitable apparatus to perform the cleaning operation. The apparatus consists of a blower 1 to circulate nitrogen or air and a boiler 2 for vaporizing the solvent, with the necessary valves piping, etc. to carry out the process as described. This apparatus may be conveniently installed on a trailer or other portable means to facilitate its use at various locations.

In carrying out the invention, the liquefied gas installation 3, represented diagrammatically as a liquid oxygen storage vessel, and hereinafter referred to as such, is 55 emptied of its liquid oxygen content and connected at its top to the inlet line 4 and at its base to the return line 5 of the cleaning apparatus. When the vessel 3 has been connected to the cleaning apparatus, all valves throughout the system are closed. Since the temperature depends somewhat on the particular solvent used, the invention as hereinafter described in detail has been 60 described with reference to the temperature suited to the use of Freon 11 as the solvent. It is understood that minor modifications would have to be made to adapt the procedure to other solvents. To raise the temperature of vessel 3 from about between —220° F. and —297° F. to —160° F., dry gas is introduced into the system through valve 8 connected to any suitable source of gas supply, as for example, a cylinder of nitrogen, herein not shown. Residual oxygen is then purged from 65 the installation by admitting nitrogen to the system through valves 8 and 9. The nitrogen is carried by 70

inlet line 4 to the storage vessel 3 and is exhausted to the atmosphere through return line 5 and valve 12. This procedure is necessary in order to remove residual oxygen and solids such as CO_2 which may contain acetylene or other hazardous material. When nitrogen is exhausting freely from valve 12, valves 8 and 12 are closed and valve 19 is opened. The blower is then started and nitrogen is circulated in a closed system. Pressure gauge 14 located downstream of blower 1 indicates the pressure in the system at this stage of operation and valve 9 located downstream of gauge 14 is provided as a throttling means to maintain the system at approximately 5 p.s.i.g. If the system requires additional gas, it may be admitted through valve 25, likewise connected to a suitable source of gas supply. The heat of compression in the blower results in a rise in temperature of the circulated gas passing through said blower. This rise in temperature serves in turn to heat the liquid installation. If temperature gauge 15 located upstream of blower 1 indicates that the gas from the storage vessel 3 is too cold, valve 6 may be partially opened to recirculate a portion of the warm gas directly to the blower. Also, if there is ample dry gas available for addition to the system, cold gas may be discharged at valve 12.

When the temperature of gas from the storage vessel 3 is warmed to about -160° F. , as indicated by temperature gauge 10, located in return line 5 downstream of storage vessel 3, all valves throughout the system are closed. The nitrogen is then disconnected from valve 8. Valves 8 and 19 are then opened and a partial vacuum is pulled on the storage vessel by throttling the system at valve 9 and using the blower 1 as a vacuum pump. Pressure gauge 13 upstream of blower 1 will indicate the extent of the vacuum obtained, either as limited by the design conditions of the vessel being cleaned or the maximum of the blower. When said vacuum has been obtained, all valves throughout the entire system are closed.

A suitable solvent is admitted to the boiler 2 through valve 16 and heater 17 is started in order to vaporize the solvent. When the pressure indicated at pressure gauge 18 rises to 5 p.s.i.g., valve 7 is opened. Solvent vapor is passed through valve 7 and inlet line 4 to the storage vessel 3 where it condenses on the walls of said vessel, washing it as it runs down the walls and collects in the bottom of the vessel. The oil-contaminated solvent is returned to the boiler 2 by way of valve 11 through return line 5. When liquid samples taken at valve 12 indicate that the vessel is clean, the heater 17 is shut off, the Freon boiler 2 is shut down and valves 7 and 11 are closed. Valves 9 and 19 are then opened, blower 1 is started and circulation of nitrogen is commenced with said nitrogen introduced at valve 25. When the pressure at gauge 14 falls below 5 p.s.i.g., additional nitrogen is introduced at valve 25; all other valves must be closed when this step is initiated and valve 9 may be used as a throttling means to maintain the system at 5 p.s.i.g. If the temperature of the gas coming to blower 1 from storage vessel 3 should be too cold, as indicated by temperature gauge 15, a portion of the warm circulating gas from the blower may be returned to the blower through valve 6. The remaining condensed solvent is then returned to boiler 2 through valve 11. Circulation of nitrogen-containing residual solvent vapor is continued until temperature gauge 10 shows that the vessel 3 is warmed to a temperature above the ambient air temperature. At this point the nitrogen is disconnected from valve 25. Valve 25 is then opened to the ambient air, valves 3 and 11 are closed and valve 12 is opened as an exhaust to the atmosphere. Warm ambient air is blown into the vessel 3 by blower 1, past valve 9, through inlet line 4 to the storage vessel 3 and is exhausted through return line 5 and valve 12. It is necessary to heat the circulated ambient air to a tem-

perature above the temperature of the system before admitting it to vessel 3. In operation the air is normally heated to about $+100^{\circ}\text{ F.}$ by the heat of compression of the blower. If vessel 3 is colder than the ambient air, condensation of the moisture in the air will take place on the walls of the vessel. When all lines of the system are blowing free and warm, the vessel is ready to be restored to service. Nitrogen and air are inert with respect to both the storage vessel 3 and the liquid oxygen in the vessel. The term inert drying gas as used herein shall be construed to mean a drying gas which is inert with respect to the installation equipment and to the liquefied gas contained therein, and not a drying gas which is inert per se.

While the instant invention is especially effective for degreasing liquefied gas installations generally operated at temperatures about between -220° F. and -320° F. , it will be obvious to those skilled in the art that said method of degreasing may also be used to clean installations operated at temperatures about between 0° F. and -220° F.

While only one embodiment of the invention has been shown and described herein, it is to be understood that the invention is not limited to the particular form shown, but may be used in other ways without departure from its spirit as defined by the following claims.

What we claim is:

1. A method of degreasing a liquefied gas installation with a degreasing solvent which comprises removing the liquefied gas from said installation, adjusting the temperature of the liquefied gas installation to a temperature above the melting point but below the boiling point of said solvent, admitting said solvent in vapor phase to said installation whereby said vapors condense on the walls of said installation at said temperature and dissolve the soluble materials from said walls while gravitating to the bottom of said installation, said solvent being selected from a group consisting of saturated and unsaturated halogenated derivatives of methane and ethane having melting points about between -124° F. and -256° F. and boiling points about between $+187^{\circ}\text{ F.}$ and -41° F. , withdrawing said condensed vapors containing said materials therefrom, and removing moisture from said installation by passing therethrough an inert drying gas in an amount effective to remove said moisture.

2. The method according to claim 1 in which said degreasing solvent corresponds to the general formula: $\text{C}_w\text{H}_x\text{Cl}_y\text{F}_z$ where w is an integer from one to two; x is an integer from zero to one; y and z are integers from zero to four; and the sum of w , x , y , and z equals from five to eight.

3. The method according to claim 1 in which said degreasing solvent is trichloromonofluoromethane.

4. A method of degreasing a liquefied gas installation comprising removing the liquefied gas from said installation, heating said installation to a temperature of about -160° F. , admitting trichloromonofluoromethane in vapor phase to said installation whereby said vapors condense on the walls of said installation at said temperature and remove grease and like materials therefrom as said condensed vapors gravitate to the bottom of said installation, removing said condensed vapors containing grease and like materials from said installation, and purging said installation by the passage therethrough of dry nitrogen followed by air, the temperature of the air being above the temperature of the nitrogen.
